UNITED STATES PATENT OFFICE.

ROBERT MILLER, OF CORTLAND, NEW YORK.

NEEDLE-HOLDER.

SPECIFICATION forming part of Letters Patent No. 697,866, dated April 15, 1902.

Application filed December 5, 1901. Serial No. 84,730. (No model.)

To all whom it may concern:

Be it known that I, ROBERT MILLER, a citizen of the United States, and a resident of Cortland, in the county of Cortland and State 5 of New York, have invented a new and Improved Toilet Article, of which the following is a full, clear, and exact description.

This invention relates to a means for conveniently carrying articles used in sewing, to 10 provide for repair of garments in case of accident while on excursions or traveling.

In carrying into effect the features of the invention I arrange the appurtenances for sewing in connection with a toilet article— 15 such as a comb, a hair ornament, or a hat-pin—so that the toilet article will serve as a casing therefor and be adapted for use in the usual way, but permit a ready removal of the sewing implements and material as occasion 20 my require.

The invention consists in the novel construction and combination of parts, as is hereinafter described, and defined in the appended claims.

25 Reference is to be had to the accompanying drawings, forming a part of this specification, in which similar characters of reference indicate corresponding parts in all the figures.

Figure 1 is a side view of the device. Fig. 30 2 is a sectional side view of the same. Fig. 3 represents a thimble constructed in accordance with my invention, and Fig. 4 is a perspective view of other novel details employed.

In effecting the object of my invention a 35 shank 5 is provided, which is shown broken in the drawings, but in service may be extended sufficiently to form the body of a pin that may be that portion of a hair ornament or a hat-pin, or said shank may be curtailed 40 in length and afford means for connecting the novel details with the head portion of a back-comb.

The upper portion of the shank 5 is tubular, and said tubular portion 5^a is open at the 45 top end, the diameter of this hollow end of the shank being sufficient to adapt it to serve as a case, wherein one or more needles a are carried.

Upon the hollow portion 5^a of the shank 5 50 three disks 6 7 8 are mounted and secured, these being suitably spaced apart, as shown

in Figs. 2 and 4. The disk 8, which is farthest removed from the open end of the shank portion 5^a, may be of greater diameter than that of the disks 6 and 7, and on its circular 55 edge a fine screw-thread b is formed. It will be seen that the portions of the shank intervening between the disks 6 7 8 form the bodies of two spools and that the disks afford end flanges therefor, so that thread of two 60 kinds may be wrapped upon these spools, as shown at c in Figs. 2 and 4.

A thimble 9 of usual form and having its end portion suitably roughened for service in sewing is provided as a casing for the 65 spools that are formed on the end portion 5^a of the shank 5, and upon the inner surface of the thimble at its edge a thread b' is formed, the internal diameter of the open end of thimble and pitch of the thread therein permitting 70 the thimble to be screwed upon the thread b, and thus detachably connect the thimble with the disk or flange 8.

The thimble 9 may be ornamented by chasing its band—that is, at and near the open end 75 thereof—and be formed of precious metal or be plated therewith to render it ornamental.

Obviously when in place the thimble 9 affords a head for the shank 5, protects the open end of the needle-case, and adapts the 80 article of personal wear to be efficient in service, as well as a unique embellishment.

It is apparent that in case the wearer of the improved hair ornament or hat-pin should have occasion to repair a rent accidentally 85 formed in an article of dress while being worn the improvement enables such temporary repairs to be effected, and thus serves the dual purpose of an article of personal use and convenient means for relieving the 90 wearer in an emergency.

Having described my invention, I claim as new and desire to secure by Letters Patent—

1. A toilet article embodying a shank hollow at one end forming a needle-case in said 95 end, a plurality of disks spaced and secured on the hollow portion of the shank, thus providing thread-spools integral therewith, and a thimble-like casing removably secured on the disk farthest from the hollow end, thus 100 affording a cover for the open end of the case and for the spools.

2. A toilet article, embodying a shank hollow at one end, disks secured at intervals upon the hollow portion of the shank, one disk having its edge screw-threaded, and a
5 thimble-like casing adapted to screw upon the threaded edge of the disk.

In testimony whereof I have signed my

name to this specification in the presence of two subscribing witnesses.

ROBERT MILLER.

Witnesses:

Mrs. ROBERT MILLER,
IRVING H. PRIDE.
